UNITED STATES PATENT OFFICE.

ARNOLD GRAVES, OF FRINTON-ON-SEA, ENGLAND.

VEHICLE LAMP.

Application filed July 19, 1922, Serial No. 575,996, and in Great Britain July 23, 1921.

This invention relates to lamps fitted with reflectors and used for head and side lights in vehicles, of the type in which the light source in combination with a small hemispherical mirror is placed inside a parabolic or similar reflector, part of the light from the source falling directly on to the reflector and part on to the mirror whence it is reflected on to the reflector. In this type one half only of the hollow surface of the reflector is used and the other half is commonly suppressed.

One of the objects of the invention is to overcome the difficulty found with reflectors commercially obtainable, that the optimum position is not always at the geometrical focus as it would be in the case of a perfect mirror.

Another object of the invention is to suppress rays above the horizontal and to cast the light in a low flat topped beam and so abolish glare, and further to make the beam as uniform as possible.

A further object is to enable the user of the lamp to vary the nature of the beam at will.

To attain the first object, the invention consists in mounting the source of light (which may be the filament of an incandescent electric lamp) together with the small hemispherical mirror (which may be formed by silvering one half of the spherical bulb of the lamp) on the holder which is capable of movement in all three dimensions, so that the source of light together with the mirror may be brought to the optimum position in the reflector and there fixed.

To attain the second object of the invention, the light source is positioned relatively to the reflector so that it is situated not at the focus or optimum position of the reflector but in advance or in rear thereof according to whether the lamp is one in which the upper half of the reflector is being used or whether it is one employing the lower half of the reflector, and to make the beam uniform it is further preferred to position the light source relatively to the hemispherical mirror so that it is not at the centre of curvature thereof but slightly in front or in rear of the centre of curvature and in the same plane.

To attain the third object, the invention consists in so mounting the light source and the small mirror that they may at will be

advanced or withdrawn along the axis of the reflector or parallel thereto, so that the light source may at will be brought to the focus of the reflector or withdrawn from it. 60 Or in the case where the source of light is an electric lamp, the lamp may be made with two filaments, one in advance of the other on the axial line, and instead of moving the lamp bodily, either of the filaments may at 65 will be switched on. One of these filaments is placed at the focus or optimum position of the reflector, and the other is so situated in relation to the first that it is in advance or in rear of the optimum position according as the upper or lower half of the reflector is used.

In the accompanying drawings which illustrate the manner in which these objects are accomplished:—

Figure 1 is a diagram illustrating one way of carrying the invention into effect in connection with an upper reflector.

Figure 2 is a view similar to Figure 1 but showing an embodiment using a lower reflector.

Figure 3 is a view illustrating the embodiment of the invention in a complete unit.

Figure 4 is a detail view further illustrating the adjusting means for the lamp.

Figure 1 shows a parabolic reflector A whose axis is represented by the line X—X and the focus is at F. M is a small semi-circular mirror whose centre of curvature is at C. L and L² are sources of light, the former of which is situated in advance of the focus F of the reflector in the same plane as the centre of curvature C of the mirror M but slightly in rear of it. The mirror will produce an image L' of L on the other side of the centre of curvature. Ignoring for a moment the effect of the image at L', the light from L as reflected by A will produce a converging beam which after coming to a focus will again diverge to give a beam in front of the lamp and below the horizontal axis X—X and this beam will have a semi-circular section with a flat top consisting of a concentric series of semi-annuli with dark interspaces. The position of L may be so adjusted relatively to M that the image L' will cast a similar beam whose semi-annuli will be coincident with the dark interspaces of the beam cast by L. The result of this will be a nearly homogeneous beam of semi-circular section with a flat top below the horizontal and free from glare but well

adapted to illuminate the road in front of the vehicle.

These remarks show the advantages to be obtained by positioning the light source L away from the centre of curvature of the hemispherical mirror M inasmuch as this arrangement renders the beam more uniform but if desired the light source L may be placed at the centre of curvature of the hemispherical mirror M and in such case the beam will be free from the glare effect provided of course that the other important feature be presented, that is to say, that the light source L shall not be at the focus F of the reflector.

As previously indicated in Figure 1 the filament L² is coincident with the focus or optimum position F of the reflector A, and when it is rendered incandescent the concentrated beam is obtained. The relationship of the filament L and its image L' is as previously described, and when a flat-topped anti-dazzle beam is required, the filament L² is extinguished and L rendered incandescent.

Figure 2 is similar to Figure 1, but in this case the lower half of the reflector is used.

Figures 3 and 4 illustrate a practical method of carrying the invention into effect. An outer shell 1 together with a base 2 is mounted on a rigid frame 4 provided with lugs 3 by means of which it may be attached in any desired position. Within this rigid frame 4 is mounted a frame 5 carrying a parabolic reflector 6. The frame 5 is capable of slight movement about pivots 7 under the influence of the screw and spring adjustment 8 by means of which it may be tilted if desired. The lamp 9 has its lower portion 10 silvered and is mounted on a cylindrical spindle 10^a which passes through a split collar 10^b mounted on the centre of a washer 18. This washer 18 is held between two rings 17 and 17^a the latter projecting through the plate 13. The apertures of the rings 17, 17^a, and the plate 13 are of greater diameter than the spindle. If the screws 19 be loosened the spindle may be moved in any direction radial to the axis of the reflector and may be fixed in the optimum position by tightening up the screws 19. Longitudinal movement of the lamp may then be effected by loosening the milled head on the split collar 10^b and tightening up again when the lamp has received sufficient axial movement to bring the source of light in advance of the focus of the reflector. The adjustment of the beam may be effected by placing the lamp so as to cast a beam on to a vertical wall about 10 feet away and moving the bulb until the beam is as bright as possible, this will occur when the filament is in the optimum point of the reflector. The lamp is then moved axially forwards until the beam assumes a flat top semi-circular

shape without glare and the milled head screwed tight. The plate 13 is mounted on a spindle 14 passing through a fixed block 15 and is capable of being pulled backwards by the Bowden wire 12 against the action of a spring 16 so that at will the driver may alter the character of the beam.

It is obvious that in the case of an existing lamp having a parabolic or similar reflector, such lamp might be converted to work in accordance with the invention by fixedly adapting to the reflector an attachable fitting carrying movably mounted therein a source of light, and a small hemispherical mirror, the source of light and the mirror being in fixed relationship but capable of adjustment in the fitting (as previously described relatively to the reflector A) in three directions, so that the source of light is capable of being brought to the focus or optimum position of the reflector and then withdrawn therefrom to another axial position by movement in the adapter fitting.

Claims:

1. A lamp of the class described including an outer shell, a main frame within said shell, a reflector carrying frame pivotally mounted in said main frame, screw means for adjusting the reflector carrying frame with reference to the main frame, a lamp carrying unit including a plate having a spindle, a fixed block on the main frame for receiving the spindle, a spring confined between the spindle and the block, a flexible connection for said spindle whereby the same may be shifted in the block to move the lamp carrier axially of the reflector, and means for moving said lamp radially to the axis of the reflector.

2. In a lamp, the combination of a frame, a carrier guided on the frame for rectilinear movement thereupon between two limiting positions, a reflector, means for mounting the reflector on the frame, said means having an adjustment for bringing the axis of the reflector into parallelism with the path of movement of the carrier, an electric light, means for mounting the lamp upon the carrier, said means having adjustment for bringing the filament of the light into the focus of the reflector when the carrier is in one limiting position, and operator controlled means for shifting the carrier from one limiting position to the other with respect to the frame to change the character of the beam emitted by the lamp while the lamp is in use.

3. In a lamp, the combination of a frame, a carrier guided on the frame for rectilinear movement thereupon between two limiting positions, a reflector, means for mounting the reflector on the frame, said means having an adjustment for bringing the axis of the reflector into parallelism with the path of movement of the carrier, an electric light,

means for mounting the lamp upon the carrier, said means having adjustment for bringing the filament of the light into the focus of the reflector when the carrier is in one limiting position, and operator controlled means for shifting the carrier from one limiting position to the other with respect to the frame to change the character of the beam emitted by the lamp while the lamp is in use, a second reflector within the first reflector, the focal point of the first reflector, the lamp and the second reflector coinciding when the carriage is in the limiting position for securing a concentrated beam.

In testimony whereof I have affixed my signature hereto this 30th day of June, 1922.

ARNOLD GRAVES.
